UNITED STATES PATENT OFFICE.

WILLIAM STEPHAN, OF FORT WAYNE, INDIANA.

LOCOMOTIVE-BOILER SUPERHEATER.

977,234.

Specification of Letters Patent. Patented Nov. 29, 1910.

Application filed January 2, 1908. Serial No. 408,964.

To all whom it may concern:

Be it known that I, WILLIAM STEPHAN, a citizen of the United States of America, residing in Fort Wayne, in the county of Allen and State of Indiana, have invented a certain new and useful Improvement in Locomotive-Boiler Superheaters, of which the following is a true and exact description, reference being had to the accompanying drawings, which form a part thereof.

The present invention relates to locomotive boilers, and has for one of its objects the provision in such a boiler of a novel means for superheating the steam generated.

Further objects of the invention are to arrange and dispose the superheating means so that the invention may be employed without requiring any radical changes from the designs of boilers now in use, and without materially, if at all, increasing the dimensions of the boiler to obtain the advantages and increased capacity due to the superheating, and so that the use of the superheating means in a boiler will strengthen and improve the construction of the boiler as a whole and will not interfere with the removal or repair of the regular boiler tubes.

The various features of novelty which characterize the invention are pointed out with particularity in the claims annexed to and forming a part of this specification.

For a better understanding of the invention and the advantages possessed by it reference may be had to the accompanying drawings and descriptive matter in which I have illustrated and described one form in which it may be embodied.

Of the drawings, Figure 1 is a sectional elevation of a portion of a locomotive boiler taken on the line 1—1 of Fig. 3. Fig. 2 is a plan view of the superheater pipes, and Fig. 3 is a sectional elevation taken on the line 3—3 of Fig. 1.

In the drawings, A represents the firebox, B the boiler tube or shell proper, and C the smokebox of a locomotive boiler which in general construction may be like any of the common forms of locomotive boiler. The usual boiler tubes B' extend between the firebox and the smokebox within the shell B, being connected into the end walls A' and C' of the firebox and smokebox respectively. The smoke escapes from the smokebox through the usual opening C², above which is located the smoke stack (not

shown). On the upper side of the boiler shell B is provided the usual steam dome B².

The superheating structure comprises one or more tubular members leading from the firebox to the smokebox. In the form shown there are three of these tubular members D. Each of the tubular members D is connected at its rear end to an elbow E, which extends between the crown sheet A⁴ of the boiler and the outer wall A² of the firebox and has its lower end opening into the firebox. Each of the tubes D may be secured to this elbow in any suitable manner, as by means of the set of bolts E'. The three elbows E may form stays between the crown sheet and the top portion of the outer wall of the double walled firebox. For this purpose, as shown each elbow is formed with a seat above and parallel to the lower end of the vertical leg of the elbow and against this seat a flanged cap-like member E² closing an aperture formed in the boiler shell is secured by means of bolts E³, the arrangement being such that the bolts E³ may be readily disconnected and connected from the outside of the boiler. The forward ends of the tubes D pass through the smokebox wall C'. Tight joints are formed between the tubes D and the smokebox wall C' by means of packing rings or collars F surrounding the tubes D and held in place by means of collars F' surrounding the tubes D at the inner side of the wall C' and flanges on the tubes D outside of the wall C' and bolts F² which connect the collars F' and the flanges on the tubes. Cup shaped diaphragms D' and D² are placed in the front and rear end of each of the tubes D. These diaphragms are connected by small tubes D³ which are located within corresponding tube D and serve to provide channels through which the products of combustion pass from the elbows E to the smokebox C. Screens or nettings D⁴ are secured to the front end of each of the tubes D to prevent the escape of large solid fuel particles. The spaces within the tubes D between the diaphragms D' and D² and surrounding the small tubes D³ form the steam spaces for the steam to be superheated. In the form shown, the steam spaces of the two outer tubes D are connected near their forward ends by an arched tubular connection D⁴, and the steam spaces of the right hand and center tubes D are connected near their rear ends by a lateral pipe D⁵. A pipe

D^e leads from the upper end of the steam dome to the steam space of left hand tube D adjacent the rear end of the latter. Steam drawn from the boiler first passes from the dome B² into the tube D^e through the port D⁷ at its upper end, thence along the left hand tube D to the connection D⁴, from whence it passes into the right hand tube, and after traveling along the latter passes into the center tube D through the lateral D⁵. The branch pipes D⁸ leading from the front end of the center tube D convey the steam to the cylinders of the engine.

It will be observed that the steam while passing through each of the tubes D is subjected to a very substantial superheating action on account of the hot gases passing through the small tubes D³. In consequence, by properly proportioning the size and number of the tubes D and D³ to the capacity of the boiler any reasonable amount of superheating desired can be obtained.

The entire superheating mechanism is located above the firetubes B' proper of the boiler, and in a space which ordinarily is not occupied by such fire tubes. Indeed, the central tube D occupies the space usually occupied by the so-called dry tube which heretofore has been employed for conveying steam from the dome to the branch pipes D⁸ running to the engine cylinders. The elbow connections E take the place in part of the stays between the inner and outer walls of the firebox, and the arrangement of these elbow connections is such as to reduce the liability to injury by overheating of the front end of the crown sheet which is the portion most apt to be injured by overheating. The construction of the superheating means is simple and mechanically reliable. Only a comparatively small number of joints are required in its construction and these are so disposed as not to interfere with ready repairs to and renewals of other portions of the boiler structure, especially with repairs to and renewals of the fire tubes B' proper.

Having now described my invention, what I claim as new and desire to secure by Letters Patent is,

1. In a locomotive boiler, the combination with the boiler shell, steam dome and fire and smoke boxes, of one or more elbows secured between the crown sheet of the firebox and the outer wall of the boiler, each elbow serving as a stay rigidly connecting said sheet and wall together and arranged with one leg vertical and opening into the firebox through the crown sheet and the other leg horizontal and opening toward the smokebox, and a set of tubes leading from said other end of each elbow to the smoke box, a large pipe surrounding each set of tubes, and connections to said pipe whereby it serves as a portion of the steam pipe for

conveying steam from the top of the steam dome to the steam outlet of the boiler.

2. In a locomotive boiler, the combination with the boiler shell, steam dome, firebox and smokebox, of one or more elbows secured between the crown sheet of the firebox and the outer wall of the boiler, each elbow serving as a stay rigidly connecting said sheet and wall together and having one branch open to the firebox through the crown sheet and the other pointing toward the smokebox, of a pipe extending from said other branch of each elbow to the smokebox, a pair of diaphragms in said pipe adjacent its ends, a set of relatively small tubes located within the pipe and extending through the diaphragms, and lateral connections to the pipe between its ends whereby said pipe serves as a portion of the steam pipe for conveying steam from the top of the steam dome to the steam outlet of the boiler, and whereby the steam passing through said pipe is dried or superheated by the furnace gases passing through said tubes.

3. In a locomotive boiler, the combination with the boiler shell, steam dome, firebox and smokebox, of one or more elbows secured between the crown sheet of the firebox and the outer wall of the boiler, and having one branch open to the firebox through the crown sheet and the other pointing toward the smokebox, of a pipe extending from said other branch of each elbow to the smokebox, a pair of diaphragms in said pipe adjacent its ends, a set of relatively small tubes located within the pipe and extending through the diaphragms, and lateral connections to each pipe between its ends whereby said pipe serves as a portion of the steam pipe for conveying steam from the top of the steam dome to the steam outlet of the boiler, and the steam passing through said pipe is dried or superheated by the furnace gases passing through said tubes, and a screen across the smokebox end of each pipe to prevent large pieces of fuel from being carried into the smokebox.

4. In a locomotive boiler the combination with the boiler shell, steam dome and fire and smoke boxes of one or more elbows each arranged with one downwardly extending vertical leg secured at its lower end to the crown sheet of the boiler and opening therethrough into the firebox and with the other leg horizontal and opening toward the smokebox, each elbow being formed with a seat at its upper side and parallel to and above the lower end of the vertical leg of the elbow, a cap member engaging the outer wall of the boiler and bolted against said seat whereby said elbow serves as a stay rigidly connecting the crown sheet and the outer wall of the boiler and a set of tubes leading from the end of the horizontal leg of each elbow to the smokebox a large pipe

surrounding each set of tubes and connections to said pipe whereby it serves as a portion of the steam pipe for conveying steam from the top of the steam dome to the steam outlet of the boiler.

5. In a locomotive boiler the combination with the boiler shell, steam dome, firebox, smokebox and the main set of tubes connecting adjacent ends of said boxes of three 10 pipes arranged side by side above said set of tubes and connecting each at its opposite ends to the fire and smoke boxes, diaphragms in said pipes adjacent their ends, a set of tubes located in each pipe and open through 15 the end connection thereof to the fire and smoke boxes whereby a superheating space is formed in each pipe between its dia-

phragms and surrounding the tubes inclosed by it, a steam outlet connection leading from the superheating space of the central pipe at 20 its smoke box end, a connection between the superheating space of the central pipe and one of the other pipes adjacent their firebox ends, a steam supply pipe leading from the upper end of said steam dome to the super- 25 heating space of the third pipe and a transverse pipe extending over the central pipe adjacent its smoke box end and connecting the superheating spaces of the other two pipes.
